UNITED STATES PATENT OFFICE

2,008,694

POWER EXCAVATOR

Walter Ferris, Milwaukee, Wis., assignor to
 Bucyrus-Erie Company, South Milwaukee, Wis.,
 a corporation of Delaware

Application August 29, 1931, Serial No. 560,077

14 Claims. (Cl. 214—135)

My invention relates to new and useful improvements in power excavators, loaders, and the like; and particularly to hydraulic drive systems therefor.

5 The present application is for an improvement over the invention described in my copending Patent No. 1,793,438, issued February 17, 1931.

One object of the present invention is the provision of an efficient drive system, through which 10 the power derived from a single prime mover may be advantageously applied to effect the several motions characteristic of machines of the type mentioned, without sacrificing the flexibility of operation and ease of control ordinarily found in steam driven machines of this type.

15 A further object of this invention is to provide means for relieving the prime mover of excessive peak loads, by hydraulically storing up energy during times of small direct load, to be 20 used at times when there would otherwise be excessive demands on the prime mover.

25 A more particular object of the present invention is to supply a device for automatically discontinuing the hydraulic storage of energy whenever a certain predetermined maximum of energy has been so stored, and also during all such 30 times as the direct demands upon the prime mover are heavy; and for automatically resuming the storage of energy whenever neither of these conditions exists.

35 Since my invention thus to a large extent evens off peak loads, it allows the use of smaller, and therefore less expensive prime movers.

In addition to the objects stated above, I have 40 worked out a number of novel and useful details, which will be readily evident as the description progresses.

45 My invention consists in the novel parts, and in the combinations and arrangements thereof, which are defined in the appended claims; and of which one embodiment is exemplified in the accompanying drawings, which are hereinafter particularly described and explained.

Throughout the description, the same reference 50 number is applied to the same member or to similar members.

Referring to the drawings, it will be seen that:

55 Figure 1 is a fragmentary plan view of a power shovel equipped with a hydraulic drive system embodying the present invention.

Figure 2 is a side elevation of certain elements shown in Figure 1.

Figure 3 is a somewhat diagrammatic representation of the essential parts of my drive system, with the details of my device for automati-

cally discontinuing or resuming the storage of energy.

The power shovel selected for illustration is of a well known type. It includes a truck frame 10, mounted upon creeping traction mechanism, conventionally indicated at 11, and carrying a circular rack and track member 12, constituting the usual support for a revolving frame or platform 13. A pinion 14 fixed to a vertical shaft 15, journaled in the platform 13, meshes with the member 12 and coacts therewith to swing the platform about a vertical axis in a well known manner. The platform carries the usual dipper supporting boom 16 and the usual dipper hoist drum 17, controlled in the usual manner, and operated 15 through appropriate gears, 18 and 19, from an electric motor, 20, used as prime mover. The traction mechanism is driven from the gear 19 through a conventional gear train 21 and shaft 22 under the control of a clutch 23. The primary function, that of hoisting the dipper, is thus effected from the electric motor, 20, through direct mechanical connections which do not differ materially from standard practice and need not be further described. The auxiliary 20 functions, however, such as swinging and thrusting the dipper, are effected through an auxiliary hydraulic system, preferably such as will now be described.

The hydraulic system includes a high pressure 30 reservoir 24, into the bottom of which liquid is supplied from a pump 25, (which may be of any appropriate design and therefore need not be more particularly described), against a resilient cushion of compressed air in the head end of the 35 reservoir. The pump is driven by the electric motor through shaft 26. It receives liquid through a pipe 28, and discharges through a pipe 29. Pipe 29 is connected through a by-pass device 53, hereinafter described, to the base of the reservoir 40 24, in which the pump maintains a working pressure. The by-pass device 53 automatically unloads the pump when the pressure in the high pressure reservoir 24 reaches a predetermined 45 maximum, and also during all times when the direct demand on the prime mover exceeds a predetermined amount; and automatically resumes the storage of energy whenever neither of these conditions exists.

The pipe 28 leading to the pump is preferably 50 supplied with liquid under low pressure from an appropriate low pressure reservoir 30. Liquid is supplied to the bottom of the reservoir 30, against an air cushion in the head end thereof, by a gear pump 31 of a well known type. The 55

pump 31 receives its supply from an appropriate supply reservoir 32 through a pipe 33 and discharges through a pipe 34 into the base of low pressure reservoir 30. A pressure relief valve, 5 conventionally indicated at 35 connected across the supply and discharge pipes 33 and 34, determines the pressure in pipe 34 and consequently in the reservoir 30. The gear pump 31 is driven through an appropriate belt and pulley connection 10 36 from the shaft 26. Valve controlled drain pipes 37 and 38 permit the contents of the high and low pressure reservoirs to be emptied into the supply tank when out of service.

In the hydraulic system shown, two variable 15 torque hydraulic motors 39 and 39' are employed for driving the swing mechanism and the dipper thrust or crowding mechanism, respectively. Both are of the type described in my copending Patent No. 1,793,438, issued February 17, 1931.

20 They are driven by liquid supplied from the high pressure reservoir through a manifold 40 and branch pipes 41 and 41', respectively, and the liquid discharged by them is directed into the low pressure reservoir 30 through branch 25 pipes 42 and 42', respectively, and manifold 43. An appropriate cut-off valve 44 is preferably provided in each manifold 40 and 43 to be closed when the shovel is not in use. The operation of each motor is regulated and controlled by a 30 rock shaft 45, 45', through which the displacement, and consequently the torque, of each motor is varied in a manner described in said first mentioned application. Rock shaft 45 is actuated and controlled by an appropriate hand lever 46 fixed 35 thereto, and rock shaft 45' is placed under the control of a hand lever 46' loosely mounted on shaft 45 and connected to shaft 45' through appropriate linkage 47.

40 The motor 39 drives the shaft 18 through a conventional gear train comprising a pair of bevel gears 48 and 49 and a pair of spur gears 50 and 51 to swing the platform 13 in either direction under the control of lever 46; and motor 39' drives the usual skipper shaft (not shown) 45 through appropriate means such as a sprocket and chain connection 52 to thrust or retract the dipper under the control of the lever 46'.

45 From the foregoing it will be noted that in the drive system shown the hoist drum 17 is directly driven from the prime mover 20, so that practically the entire power output thereof is available for peak hoisting loads. The average power consumption of the hoist mechanism however is considerably less than the maximum power capacity of the prime mover, the difference being more than sufficient to supply the combined average power demands of the swing and thrust mechanisms. In this instance the high pressure reservoir 24 serves as a power storage medium, to 50 which power is supplied through the pump 25 from the prime mover, and by which energy from the prime mover in excess of the demands of the hoist mechanism, is rendered available to operate the swing and thrust mechanisms.

55 Figure 3 is intended to show in detail the construction of the by-pass device, 53, for unloading the pump 25, as previously explained, and to show the various connections thereto. For this reason some of the other instrumentalities have been conventionalized or omitted in the interest of clearness. Thus, in Figure 3 the storage tank, shown as 32 in Figures 1 and 2, the gear pump 31 and its connections, and the motor 39' and its governing devices, have been omitted.

60 In this figure, the electric motor 20 is shown

as driving the pump 25 through shaft 26. From low pressure tank 30, pipe 28 conveys liquid to the pump. Pipe 29 conveys the liquid to the by-pass device 53. This device has several annular chambers, 54, 55, 56, through the center of which slides a shiftable valve member, 57, said valve member being cut away at its central portion 58, as shown, so as to be capable of connecting annular space 55 with either one of the annular spaces 54 or 56. Thus, with the valve member 57 in position as shown in Figure 3, there is free communication between annular chambers 54 and 55, by way of the space surrounding the cut away portion 58 of the valve member 57.

65 Separated from the three annular spaces 54, 55, 56, and more or less surrounding them, the by-pass device 53 contains a larger space 59, which communicates directly, by pipe 60, with low pressure tank 30.

70 One end of shiftable valve member 57, consists of a stem 61, working in a chamber 62, and surrounding by a helical compression spring 63. One end of this spring bears against the shiftable valve member 57, and the other end bears against an adjusting plate 64, carried as shown 25 by a screw threaded into the end of the by-pass device 53. The spring 63 therefore exercises an adjustable thrust upon the valve member 57, tending to close annular chamber 56 and to maintain free communication between chambers 30 54 and 55. Chamber 62 communicates freely with chamber 59.

75 The other end of valve member 57 carries a portion 65, which operates as a piston in a cylindrical chamber 66. At their contiguous ends, 35 chambers 66 and 59 communicate freely.

80 From high pressure tank 24 a pipe 67 conveys liquid under pressure to pressure regulator 68. This regulator contains a valve 69 which is opened by excess pressure in tank 24 against the 40 pressure of a helical spring 70. The tension in spring 70, and therefore the pressure necessary to open valve 69, are adjustable, as shown, by the adjusting screw 71. A pipe 72 connects the pressure regulator 68, as shown, with the cylindrical chamber containing piston 65.

85 When settings of all portions of my device are as shown in Figure 3, and motor 20 is driving pump 25, through shaft 26, liquid will be pumped from low pressure tank 30, passing by 50 pipe 28 to pump 25, and thence by pipe 29 to the chamber 55. Communication between chambers 55 and 54 being open, liquid under pressure will pass, by pipe 72, to high pressure tank 24. If valve 44 is open, liquid under pressure actuates 55 variable torque motor 39, and is returned to the low pressure tank 30 by way of pipe 43.

90 Adjusting screw 71, in the head of pressure regulator 68, is supposed to be adjusted to keep valve 69 seated against any pressure less than 60 a certain predetermined maximum. When the pressure in tank 24 exceeds this maximum, it is communicated by pipe 67, to valve 69, which it raises from its seat. Liquid under pressure then flows by pipe 72 to the head of piston 65, forces 65 the piston against the pressure of spring 63, thereby closing the ports into annular space 54, and opening communication between annular spaces 55 and 56. Liquid delivered by pipe 29 into annular space 55 now no longer flows by 70 way of space 54 and pipe 72 into the high pressure tank 24, but must pass into annular space 56, and back to low pressure tank 30 by way of pipe 13. During such times, therefore, that the pressure in high pressure tank 24 is at the de- 75

sired maximum, the pump 25 is merely driving liquid from the low pressure tank, through a negligible amount of friction, back to the low pressure tank. It is therefore practically idling, leaving the full power of the motor 20 available for the instrumentality directly driven by the motor.

When, by reason of the actuation of motor 39 by the pressure in tank 24, that pressure has again become reduced below that for which the pressure regulator 68 is set, valve 69 will then close. A small tube 74 is provided in the casting which serves as cylinder for the piston 65, to allow the liquid to pass at a relatively slow rate from the high pressure side of piston 65 to the low pressure side 66. Spring 63 then restores the valve member 51 to the position shown in Figure 3, and pressure is again built up in tank 24.

But it may be desirable, or even compulsory, to use the full power of the motor 20 for the directly driven instrumentality—in this case, the hoist drum 17, shown in Figure 1—at times when tank 24 is not up to full pressure, and when valve 69, in the pressure regulator 68, is therefore closed. In order to relieve the motor in such a case, I have added the device now to be described.

Projecting an appreciable distance through the casing of the by-pass valve 53, and integral with the piston end of the shiftable valve member 51 and axial thereto, is a rod 75. Abutting the end of this rod is a rod 76, which is carried by the magnetizable core 77 of a solenoid 78. The solenoid is connected by wires 79, through an overcurrent relay (not shown) to the source that supplies power to the motor. When the demands upon the motor exceed the predetermined amount for which the overcurrent relay is set, the relay connects the solenoid to the power line, and the core 77, being drawn into the solenoid, thrusts against the rod 75, thereby closing the ports of annular space 54, opening communication between spaces 55 and 56, and relieving the motor of the task of driving the pump. When the power demand on the motor falls below the predetermined amount, the overcurrent relay cuts out the solenoid, and spring 63 restores the valve member to the position in which the storage of energy is again resumed.

Having now described and illustrated one form of my invention, I wish it to be understood that my invention is not to be limited to the specific form or arrangement of parts hereinbefore described, except in so far as such limitations are specified in the appended claims.

I claim:

1. In a power excavator, the combination of: a prime-mover; hoist mechanism, directly driven by said prime-mover; auxiliary excavating mechanism; a hydraulic pressure reservoir; a constant displacement hydraulic pump, driven by the prime-mover, and feeding the reservoir; an unloading valve, actuatable to completely unload the pump; means, adapted to move in one direction responsive to overload on the prime-mover, and adapted to move in the opposite direction when the overload ceases; means operably connecting the last named means to the unloading valve; means, adapted to move in one direction responsive to a pressure above a certain predetermined figure in the reservoir, and adapted to move in the opposite direction when the pressure falls below that figure; means operably connecting the last named means to the unloading valve; and a

controllable hydraulic motor, fed by the reservoir, and driving the auxiliary excavating mechanism.

2. In a power excavator, the combination of: a prime-mover; hoist mechanism, directly driven by said prime-mover; auxiliary excavating mechanism; a hydraulic pressure reservoir; a constant displacement hydraulic pump, driven by the prime-mover, and feeding the reservoir; an unloading valve, actuatable to completely unload the pump; means, adapted to move in one direction responsive to a pressure above a certain predetermined figure in the reservoir, and adapted to move in the opposite direction when the pressure falls below that figure; means operably connecting the last named means to the unloading valve; and a controllable hydraulic motor, fed by the reservoir, and driving the auxiliary excavating mechanism.

3. In a power excavator, the combination of: a prime-mover; hoist mechanism, directly driven by said prime-mover; auxiliary excavating mechanism; a hydraulic pressure reservoir; a constant displacement hydraulic pump, driven by the prime-mover, and feeding the reservoir; an unloading valve, actuatable to completely unload the pump; means, adapted to move in one direction responsive to overload on the prime-mover, and adapted to move in the opposite direction when the overload ceases; means operably connecting the last named means to the unloading valve; and a controllable hydraulic motor, fed by the reservoir, and driving the auxiliary excavating mechanism.

4. In a power excavator, the combination of: a prime-mover; hoist mechanism directly driven by said prime-mover; auxiliary excavating mechanism; a hydraulic low-pressure reservoir; a hydraulic high-pressure reservoir; a constant displacement hydraulic pump, driven by the prime-mover, drawing from the low-pressure reservoir, and feeding the high-pressure reservoir; a by-pass valve, actuatable to divert the pump so that it will feed back into the low-pressure reservoir; means, adapted to move in one direction responsive to overload on the prime-mover, and adapted to move in the opposite direction when the overload ceases; means operably connecting the last named means to the by-pass valve; means, adapted to move in one direction responsive to a pressure above a certain predetermined figure in the reservoir, and adapted to move in the opposite direction when the pressure falls below that figure; means operably connecting the last named means to the by-pass valve; and a controllable hydraulic motor, fed by the high-pressure reservoir, and driving the auxiliary excavating mechanism.

5. In a power excavator, the combination of: a prime-mover; hoist mechanism, directly driven by said prime-mover; auxiliary excavating mechanism; a hydraulic pressure reservoir; a constant displacement hydraulic pump, driven by the prime-mover, and feeding the reservoir; mechanism actuatable to unload the pump; mechanism directly responsive to the load on (as distinguished from the speed of) the prime mover; an operative connection whereby the last named mechanism actuates the first; mechanism responsive to the pressure in the reservoir; an operative connection whereby the last named mechanism actuates the first; and a controllable hydraulic motor, fed by the reservoir, and driving the auxiliary excavating mechanism.

6. In a power excavator, the combination of: a prime-mover; hoist mechanism, directly driven

- by said prime-mover; auxiliary excavating mechanism; a hydraulic pressure reservoir; a constant displacement hydraulic pump, driven by the prime-mover, and feeding the reservoir; mechanism actuatable to unload the pump; mechanism directly responsive to the load on (as distinguished from the speed of) the prime-mover; an operative connection whereby the last named mechanism actuates the first; and a controllable hydraulic motor, fed by the reservoir, and driving the auxiliary excavating mechanism.
7. In a power shovel, a frame, a boom, a dipper thereon including a reciprocably movable handle and thrust mechanism therefor, a cable drum on said frame having flexible cable connections with said dipper, a constant speed engine on said frame having optional driving connection with said cable drum, a hydraulic system comprising a pump driven by said engine, a high pressure line and a low pressure line, a hydraulic motor for said thrust mechanism between said high and low pressure lines, a by-pass line between said latter lines, a pressure tank connected to said high pressure line, and means responsive to a predetermined pressure in said tank for opening said by-pass line to cause the pump to pump back into the low pressure line, with the pressure on both sides of the pump practically equalized.
8. In a power shovel, a base, a swinging platform thereon, mechanism for swinging said platform relative to said base, a boom on said platform supporting an excavator, a cable drum on said platform having flexible cable connections on said excavator, a constant speed engine on said platform having optional driving connections with said cable drum, a hydraulic pump driven by said engine, a high pressure line and a low pressure line, a hydraulic motor for said swing mechanism between said high and low pressure lines, a by-pass line between said latter lines, a pressure tank connected to said high pressure line, and means responsive to a predetermined pressure in said tank for opening said by-pass line to cause the pump to pump back into the low pressure line, with the pressure on both sides of the pump practically equalized.
9. In a power shovel, a frame, a boom, a dipper, auxiliary excavating instrumentalities, a cable drum on said frame having flexible cable connections with said dipper, a constant speed engine on said frame having optional driving connection with said cable drum, a hydraulic system including a pump driven by said engine, a high pressure line and a low pressure line, a hydraulic motor for one of said auxiliary excavating instrumentalities between said high and low pressure lines, a pressure tank connected to said high pressure line, and means responsive to a predetermined pressure in said tank to cause the pump to pump back into the low pressure line, with the pressure on both sides of the pump practically equalized.
10. In a machine of the character described, a prime-mover, a hoisting winch having optional direct driving connection with the prime-mover, a hydraulic pump driven by said prime-mover, a high pressure line, a low pressure line, hydraulic power devices connected between said high and low pressure lines, a by-pass line connected between said high and low pressure lines and having a pressure responsive valve therein characterized by being operable to wholly unload the pump by causing it to pump directly back into the low pressure line against merely the pressure in the low pressure line, a pressure tank connected to said high pressure line, and a pipe leading from said tank to said pressure-responsive valve and supplying pressure to open the latter when the pressure in said tank exceeds a predetermined value.
11. In a power excavator, the combination of: a prime-mover; hoist mechanism, directly driven by said prime-mover; auxiliary excavating mechanism; a hydraulic pressure reservoir; a constant displacement hydraulic pump, driven by the prime-mover, and feeding the reservoir; an unloading valve, actuatable to completely unload the pump; means biasing this valve to remain in or return to its non-unloading position; a hydraulic piston, so operatively associated with the unloading valve, as to move the unloading valve to unloading position, when actuated; a pressure responsive valve, adapted to admit hydraulic fluid from the reservoir to the piston, whenever the pressure in the reservoir exceeds a predetermined maximum; a solenoid, so operatively associated with the unloading valve as to move the unloading valve to unloading position, when actuated; means to actuate the solenoid whenever the load on the prime-mover exceeds a predetermined maximum; and a controllable hydraulic motor, fed by the reservoir, and driving the auxiliary excavating mechanism.
12. In a power shovel, a frame, a boom, a dipper, auxiliary excavating instrumentalities, a cable drum on said frame having flexible cable connections with said dipper, a constant speed engine on said frame having optional driving connection with said cable drum, a hydraulic system including a pump driven by said engine, a high pressure line and a low pressure line, a hydraulic motor for one of said auxiliary excavating instrumentalities between said high and low pressure lines, a pressure tank connected to said high pressure line, and means responsive to a predetermined pressure in said tank to shut off said tank from both the low pressure line and the outlet of the pump, and at the same time connect the outlet of the pump to the low pressure line.
13. In a power shovel, a frame, a boom, a dipper, auxiliary excavating instrumentalities, a cable drum on said frame having flexible cable connections with said dipper, a constant speed engine on said frame having optional driving connection with said cable drum, a hydraulic system including a pump driven by said engine, a high pressure line and a low pressure line, a hydraulic motor for one of said auxiliary excavating instrumentalities between said high and low pressure lines, a pressure tank connected to said high pressure line, a valve characterized as follows: the valve has two positions, namely: (1) the outlet of the pump is connected to the entire high pressure line, and the low pressure line is shut off from both; and (2) the high pressure line is blocked between the pump and the tank, and that part of the high pressure line between the pump and the valve is connected to the low pressure line, position No. 1 being the normal position; means responsive to tank-pressure above a predetermined maximum to cause the valve to assume position No. 2; and means to restore the valve to position No. 1 when the pressure drops below this maximum.
14. In a power shovel, a frame, a boom, a dipper, auxiliary excavating instrumentalities, a cable drum on said frame having flexible cable connections with said dipper, a constant speed engine on said frame having optional driving

135

2,008,694

5

connection with said cable drum, a hydraulic system including a pump driven by said engine, a high pressure line and a low pressure line, a hydraulic motor for one of said auxiliary excavating instrumentalities between said high and low pressure lines, a pressure tank connected to said high pressure line, a valve characterized as follows: the valve has two positions, namely (1) the outlet of the pump is connected to the entire high pressure line, and the low pressure line is shut off from both; and (2) the high pressure line is blocked between the pump and the tank, and that part of the high pressure line between the pump and the valve is connected to the low pressure line, position No. 1 being the normal position; means responsive to tank-pressure above a predetermined maximum to cause the valve to assume position No. 2; means responsive to load on the engine above a predetermined maximum to cause the valve to assume position No. 2; and means to restore the valve to position No. 1 when both the pressure and the load drop below their respective maxima.

5
WALTER FERRIS.
